PENDANT WATCH

Ernest Schneider, % Sicura Watch Co. Ltd., P.O. Box 108,
Grenchen, Switzerland

Filed July 6, 1966, Ser. No. 2,955

Claims priority, application Switzerland Jan. 6, 1966

Term of patent 3½ years

(Cl. D42—8)

I claim:

The ornamental design for a pendant watch, as shown.
